PROCESS FOR BREAKING PETROLEUM EMULSIONS

Melvin De Groote, St. Louis, Mo., assignor to The Tret-O-Lite Company, Webster Groves, Mo., a corporation of Missouri

No Drawing. Application June 21, 1937,
Serial No. 149,472

10 Claims. (Cl. 196—4)

This invention relates to the treatment of emulsions of mineral oil and water, such as petroleum emulsions, for the purpose of separating the oil from the water.

5 Petroleum emulsions are of the water-in-oil type, and comprise fine droplets of naturally-occurring waters or brines, dispersed in a more or less permanent state throughout the oil which constitutes the continuous phase of the emulsion.

10 They are obtained from producing wells and from the bottom of oil storage tanks, and are commonly referred to as "cut oil", "roily oil", "emulsified oil" and "bottom settling".

15 The object of my invention is to provide a novel and inexpensive process for separating emulsions of the character referred to into their component parts of oil and water or brine.

Briefly described, my process consists in subjecting a petroleum emulsion of the water-in-oil type to the action of a treating agent or demulsifying agent of the kind hereinafter described, thereby causing the emulsion to break down and separate into its component parts of oil and water or brine, when the emulsion is permitted to remain in a quiescent state after treatment, or is subjected to other equivalent separatory procedures.

20 The treating agent or demulsifying agent contemplated by my process consists of a sulfopolyhydric alcohol ester of a detergent-forming carboxy acid, of the kind hereinafter described in detail.

25 It has long been known that various organic acids of fairly high molecular weight, combine with alkalis to produce soap or detergent-like materials. Such acids include the higher fatty acids derived from animal or vegetable sources, such as oleic acid, stearic acid, palmitic acid, ricinoleic acid, etc. Acids derived from rosins such as abietic acid represents another class. Similarly, carboxy acids derived from petroleum, such as various naphthenic acids, represent a third class. It is also well known that these various detergent-forming acids can be modified 30 so as to produce equivalent derivatives, which have the same functional properties. For instance, chlorinated or brominated oleic acid produces detergent-like materials, and such an acid is classified as a detergent-forming acid. Similarly, fatty sulfonic acids, fatty acid sulfates, or sulfo-aromatic fatty acids represent detergent-forming carboxy acids which combine with alkalis to produce detergents or detergent-like materials. Similarly, hydrogenated abietic acid or sulfonated abietic acid will serve as satisfactorily for

the formation of a detergent as abietic acid itself, and such functional derivatives are considered as detergent-forming acids.

Reference is made to U. S. Patent #1,988,835, to De Groote and Wirtel, dated January 22, 1935. 5 This particular patent describes a process for breaking petroleum emulsions of the water-in-oil type, which consists in subjecting the emulsion to the action of a demulsifying agent containing a sulfo-aliphatic ester of a fatty acid of the type $R''\cdot COO(T\cdot SO_3\cdot Z)$, in which R'' is a fatty acid radical, COO is a carboxyl residue, T is the aliphatic residue, SO_3 is the conventional sulfonic acid residue, Z represents the acidic hydrogen atom of the sulfonic acid or its equivalent, and $(T\cdot SO_3\cdot Z)$ replaces the carboxylic hydrogen. 10 15

Reference is also made to U. S. Patent #2,077,-745, to De Groote, dated April 20, 1937. This particular patent describes a process for breaking 20 petroleum emulsions of the water-in-oil type, which consists in subjecting the emulsion to the action of a demulsifying agent of the kind indicated by the type formula:

25 $R\cdot COO\cdot T\cdot (OH)_n\cdot (SO_4\cdot Z)_m$

in which $R\cdot COO$ is the carboxy acid radical derived from a detergent-forming carboxy acid; $T\cdot (OH)_n$ is the residue from a polyhydric alcohol; SO_4 is the sulfate radical; and Z is the 30 ionizable hydrogen equivalent; n represents the numeral 0, 1 or more; and m represents the numeral 1 or more.

Reference is also made to U. S. Patent #2,052,-284, to De Groote, dated August 25, 1936, which 35 describes a process for breaking petroleum emulsions by the action of a demulsifying agent comprising a chemical compound of the formula type: $(R\cdot COO)_m\cdot T\cdot (OH)_n$, in which $R\cdot COO$ represents a non-sulfo, detergent-forming, monocarboxy 40 acid radical, T represents a polyhydric alcohol residue, and m indicates the numeral 1 or more, and R and T being additionally characterized by freedom from an extraneous acid residue. 45

I have found that certain oil field emulsions which, although susceptible to 1 or more of the types of demulsifying agent previously described, are even more susceptible to a reagent characterized by being of the following type formula:

50 $R\cdot COO\cdot T\cdot (OH)_n\cdot (SO_3\cdot Z)$

in which $R\cdot COO$ is a carboxy acid radical derived from a detergent-forming carboxy acid, $T\cdot (OH)_n$ is a residue derived from a polyhydric alcohol of the kind which in unaltered form con- 55

tains at least three hydroxyls, n being the number 1, 2, or 3, and SO_3Z being the typical sulfonic acid radical, in which Z represents an ionizable hydrogen atom equivalent.

5 Compounds of the kind contemplated for use as demulsifying agents in the present process may be prepared in any suitable manner. Various methods are known for the preparation of soluble salts of 1:2 dihydroxy propane :3 sulfonic acid. Such material can be esterified with a mole of any suitable detergent-forming carboxy acid, and particularly various fatty acids or modified fatty acids of the kind previously described. Another suitable procedure is to treat 10 the soluble salts of 1 halogen :2 hydroxy propane :3 sulfonic acid with suitable fatty acid salts or the like, so as to eliminate an inorganic halide, such as sodium chloride.

15 Examples of well known procedures for producing reagents of the kind herein contemplated as demulsifying agents include the following:

Example 1

20 180 parts of the sodium salt of glycerol sulfonic acid (sodium 1:2-dihydroxy propane 3-sulfonate, prepared by heating alpha-chlorohydrin derived from glycerol with aqueous Na_2SO_3 solution and subsequent removal of water) are heated at 150° to 225° C. for 6 hours with stirring with 25 210 parts of the fatty acids from cocoanut oil, the water evolved in the reaction being allowed to escape and the fatty acids being returned to the reacting chamber by suitable reflux condensation. The product of this reaction is then purified by washing with cold ethyl alcohol or other low-boiling alcohol, or preferably by dissolving in hot ethyl alcohol, filtering to remove insoluble inorganic salts, or other insoluble matter and crystallizing from the alcoholic solution.

30 *Example 2*

35 200 parts of the sodium salt of 1-chloro 2-hydroxy propane: 3-sulfonic acid (prepared by first treating one mole of glycerine with two moles of chlorine to form $\text{CH}_2\text{Cl}-\text{CHOH}-\text{CH}_2\text{Cl}$, and then reacting one mole of this product with one 40 mole of sodium sulfite to form

45 50 are heated at 100° to 200° C. with stirring for 5 hours with 300 parts of sodium soap prepared from tallow. The product of the reaction may then be purified as in Example 1.

55 *Example 3*

55 A triethanolammonium (sometimes called triethanolamine) compound may be formed as follows:

290 parts of the sodium salt of commercial 60 stearic acid are heated at about 125° C., with stirring for 4 hours with 325 parts of the triethanolammonium salt of 1-chloro 2-hydroxy propane 65 3-sulfonic acid (prepared by heating 1:3 dichlorohydrin with triethanolammonium sulfite). The product of the reaction may be purified as in Example 1.

70 In some instances it is more economical to employ the dichlorohydrin as the raw material rather than the monochlorohydrin. The reason is that the dichlorohydrin can be prepared very economically by means of sulfur monochloride. See "Systematic Organic Chemistry", Cumming, Hopper, Wheeler, 1931, p. 335.

75 It is obvious that other polyhydroxylated materials may replace glycerol provided that they

contain at least three alcoholic hydroxyls. For instance, one could prepare the monochlorohydrin or the dichlorohydrin from diglycerol, which is an ether alcohol, and employ such material just as advantageously as a corresponding compound 5 derived from glycerol. Similarly, one could prepare an ether alcohol from diglycerol and a monohydric alcohol, such as ethyl alcohol, and employ such ether alcohol in place of glycerol, provided that the compound contained at least 10 three alcoholic hydroxyls and provided that it could be converted readily so as to yield a monochlorohydrin and a dichlorohydrin. Similarly, ether alcohols could be obtained by reaction between a glycol, such as ethylene glycol, propylene 15 glycol, or the like, and glycerol. The ether alcohols so obtained could be converted into a monochlorohydrin or a dichlorohydrin and these materials employed in the manner previously described.

20 It is understood that reference to a polyhydric alcohol or a polyhydric alcohol residue refers to the ether type as well as the non-ether type. Whenever it is intended to limit the meaning to polyhydric alcohols or polyhydric alcohol residues, as differentiated from the polyhydric alcohol ethers or polyhydric alcohol ether residues, the expression "free from an ether linkage" will be employed.

25 Although it has been pointed out that the detergent-forming carboxy acid may be supplied by a resin acid, such as abietic acid, chlorabietic acid, sulfoabietic acid, or the like, or may be furnished by a petroleum carboxy acid, such as naphthenic acid, sulfonaphthenic acid, or the like, I prefer to employ detergent-forming carboxy acids derived from fatty acids, and particularly, modified fatty acids, which are nothing more nor less than equivalent functional derivatives of a simple unchanged fatty acid, and which still 40 have the characteristic quality of combining with an alkali to give a soap or soap-like detergent. These acids are commonly referred to as "modified fatty acids". I prefer to prepare my demulsifying agent, which is a sulfopolyhydric alcohol 45 ester, from modified fatty acids.

30 The expression "modified fatty acids" is well understood by those skilled in the art of resolving petroleum emulsions of the water-in-oil type, and has been used frequently in the patent literature to designate a certain well known class of 50 materials. Briefly described, modified fatty acids are modifications of fatty acids obtained by chemical reaction on a fatty acid or its equivalent, so as to result in an addition product or 55 substitution product, and they bear a simple genetic relationship to each other or to the parent fatty acid or fatty acid compound from which they were derived. Modified fatty acids do not include salts of unmodified fatty acids, such as 60 soaps, because a salt of a fatty acid is not an addition product. Likewise, it is not a substitution product, because "substitution products" in the sense that such term is used in organic chemistry, is applied not to salts, but to undissociable 65 or indifferent compounds. Furthermore, whereas the acid hydrogen involved in salt formation can be replaced only by metals or metal-like groups, that is, elements or radicals which are electro-positive, substitution may replace the hydrogen 70 of organic compounds by a variety of elements and groups which may be electro-negative.

75 The treating agent or demulsifying agent contemplated by my process includes esters of the specific kind described, and may be derived from

either simple fatty acids; or modified fatty acids. In order to keep the distinction clear between a simple fatty acid and a modified fatty acid and yet use a term which will be inclusive of both 5 classes, the expression "fatty acid" will be used hereafter to indicate both classes of materials. A simple fatty acid is indicated by the formula R.COOH, in which R is a fatty acid radical, such as an oleic acid radical, stearic acid radical, 10 palmitic acid radical, ricinoleic acid radical, and COOH indicates the conventional carboxyl radical. If the simple fatty acid is of the unsaturated type, such as oleic acid, ricinoleic acid, etc., and one produces an addition product by means of a 15 chemical reagent, then the modified fatty acid thus obtained may be indicated by the formula R.XX.COOH, in which XX represents atoms or radicals joined in addition, such as OH, HSO₄, HSO₃, Cl, Br, C₆H₅HSO₃, C₆H₅OH, HSO₃, etc. 20 XX may represent the same atoms as in the case of oleic acid dichloride, or XX may represent an atom and a radical, as in the case of oleic acid hydrogen hydrogen sulfate. In event that the 25 simple fatty acid contained more than one ethylene linkage, such as linoleic acid, then one might obtain a modified fatty acid of the type R.XX.XX.COOH, but which is simply considered as a variety of the R.XX.COOH specie.

Just as the simple fatty acid of the type 30 R.COOH may yield addition products, likewise, it may yield substitution products, and such a modified fatty acid may be designated by the formula R'D.COOH, in which R' is a simple fatty acid radical residue, COO is a carboxyl residue and 35 D is the substituent atom or radical, such as HSO₄, C₆H₅HSO₃, phthalic acid residue, oxalic acid residue, acetic acid residue, phosphoric acid residue, chlorine, etc., or a residue of the type R''.COO, in which R'' indicates another simple or modified 40 fatty acid radical residue which may be the same as R', as in the case of poly acids, such as diricinoleic, triricinoleic, etc.

Simple fatty acids, such as ricinoleic acid, may 45 yield a modified fatty acid which is both an addition and substitution product. For instance, ricinoleic acid may yield a modified fatty acid, which is both an addition and a substitution product, and may be indicated by the formula R'D.XX.COOH, in which the various symbols 50 have the same significance, as previously. The formula R.COOH includes fatty acids, such as oleic acid, ricinoleic acid, stearic acid, etc. The formulas R.XX.COOH, R'D.COOH, and R'D.XX.COOH include the conventional modified 55 fatty acids. Fatty acids include the class comprising

R.COOH
R.XX.COOH
R'D.COOH
R'D.XX.COOH

60 in which the symbols have their previous significance. The above formulas indicate the simple genetic relationship existing among the members of the class. For sake of simplicity, hereafter R_cCOOH will be used to designate either the simple or modified fatty acids, without distinction, except when the context denote a specific meaning.

70 The treating agent or demulsifying agent which I prefer to employ in my present process is obtained by reacting molecular proportions of the sodium salt of glycerol sulfonic acid with 1:2-dihydroxy propane 3-sulfonate, prepared by heating 75 alphachlorhydrin with aqueous Na₂SO₃ solution

and subsequent removal of water, with ricinoleic acid. The reaction takes place rather rapidly at 150-220° C., and is generally complete after 10 hours. It is most readily conducted by constant stirring and by the passage of a dry inert gas, 5 such as dry carbon dioxide. Suitable means must be employed to prevent the escape of any of the free fatty acids. The product may be employed as such or may be purified in the manner previously described in Example 1 above. The product so obtained may be characterized by the formula (C₃H₅)XXSO₃Z, in which one occurrence of X represents a hydroxyl and the other occurrence represents a ricinoleic acid or polyricinoleic acid 10 radical.

15 The reagents previously described were obtained in the form of salts. Needless to say, they may be acidified so as to liberate the free acid and the free acid may be employed for purposes of demulsification. The free acid may be neutralized 20 with any suitable base or may be esterified with a suitable alcohol. In other words, the carboxyl radical may be combined with a suitable base such as caustic soda, caustic potash, ammonium hydroxide, etc., or with a suitable amine, 25 such as pyridine, aniline, triethanolamine, amylamine, cyclohexylamine, benzylamine, and the like. The material may be combined with such materials as calcium or magnesium oxide or a carbonate. The materials may be combined so as 30 to produce heavy metal salts, such as the iron salts, copper salts, etc. Carboxylic hydrogen atoms, if present, may be esterified with a monohydric alcohol, such as methyl alcohol, ethyl alcohol, propyl alcohol, etc., or may be esterified 35 with a polyhydric alcohol, such as glycerol, ethylene glycol, and the like.

Conventional demulsifying agents employed in the treatment of oil field emulsions are used as such, or after dilution with any suitable solvent, 40 such as water; petroleum hydrocarbons, such as gasoline, kerosene, stove oil; a coal tar product, such as benzene, toluene, xylene, tar acid oil, cresol, anthracene oil, etc. Alcohols, particularly aliphatic alcohols, such as methyl alcohol, 45 ethyl alcohol, denatured alcohol, propyl alcohol, butyl alcohol, hexyl alcohol, octyl alcohol, etc., may be employed as diluents. Miscellaneous solvents, such as pine oil, carbon tetrachloride, sulfur dioxide extract obtained in the refining of 50 petroleum, etc., may be employed as diluents. Similarly, the material or materials employed as the demulsifying agent of my process may be admixed with one or more of the solvents customarily used in connection with conventional demulsifying agents. Moreover, said material or 55 materials may be used alone or in admixture with other suitable well known classes of demulsifying agents, such as demulsifying agents of the modified fatty acid type, the petroleum sulfonate type, the alkylated sulfo-aromatic type, etc.

It is well known that conventional demulsifying agents may be used in a water-soluble form, or in an oil-soluble form, or in a form exhibiting 60 both oil and water solubility. Sometimes they may be used in a form which exhibits relatively limited water solubility and relatively limited oil solubility. However, since such reagents are sometimes used in a ratio of 1 to 10,000 or 1 to 65 20,000, or even 1 to 30,000, such an apparent insolubility in oil and water is not significant, because said reagents undoubtedly have solubility within the concentration employed. This same 70 fact is true in regard to the material or materials 75

employed as the demulsifying agent of my process.

I desire to point out that the superiority of the reagent or demulsifying agent contemplated in my process is based upon its ability to treat certain emulsions more advantageously and at a somewhat lower cost than is possible with other available demulsifiers, or conventional mixtures thereof. It is believed that the particular demulsifying agent or treating agent herein described will find comparatively limited application, so far as the majority of oil field emulsions are concerned; but I have found that such a demulsifying agent has commercial value, as it will economically break or resolve oil field emulsions in a number of cases which cannot be treated as easily or at so low a cost with the demulsifying agents heretofore available.

In practising my process, a treating agent or demulsifying agent of the kind described above may be brought in contact with the emulsion to be treated in any of the numerous ways now employed in the treatment of petroleum emulsions of the water-in-oil type with chemical demulsifying agents, such, for example, as by introducing the treating agent into the well in which the emulsion is produced; introducing the treating agent into a conduit through which the emulsion is flowing; introducing the treating agent into a tank in which the emulsion is stored; or introducing the treating agent into a container that holds a sludge obtained from the bottom of an oil storage tank. In some instances, it may be advisable to introduce the treating agent into a producing well in such a way that it will become mixed with water and oil that are emerging from the surrounding strata, before said water and oil enter the barrel of the well pump or the tubing up through which said water and oil flow to the surface of the ground. After treatment, the emulsion is allowed to stand in a quiescent state, usually in a settling tank, and usually at a temperature varying from atmospheric temperature to about 200° C., so as to permit the water or brine to separate from the oil, it being preferable to keep the temperature low enough to prevent the volatilization of valuable constituents of the oil. If desired, the treated emulsion may be acted upon by one or more of the various kinds of apparatus now used in the operation of breaking petroleum emulsions, such as homogenizers, hay tanks, gun barrels, filters, centrifuges, or electrical dehydrators.

The amount of treating agent that may be required to break the emulsion may vary from approximately one part of treating agent to 500 parts of emulsion, up to one part of treating agent to 20,000, or even 30,000 parts of emulsion. The proportion depends on the type of emulsion being treated, and also upon the equipment being used, and the temperature employed. In treating exceptionally refractory emulsions of the kinds known as "tank bottoms" and "residual pit oils", the ratio of 1:500, above referred to, may be required. In treating fresh emulsion, i. e., emulsions that will yield readily to the action of chemical demulsifying agents, the ratio of 1:30,000, above referred to, may be sufficient to produce highly satisfactory results. In general, I have found that for an average petroleum emulsion a ratio of one part of treating agent to 5,000 parts or 10,000 parts of emulsion will usually be found to produce commercially satisfactory results.

Having thus described my invention, what I claim as new and desire to secure by Letters Patent is:

1. A process for breaking petroleum emulsions of the water-in-oil type, which consists in subjecting the emulsion to the action of a demulsifying agent comprising a compound of the formula type:

in which R.CO.O is a carboxy acid radical derived from a detergent-forming carboxy acid; T(OH)_n is a residue derived from a polyhydric alcohol of the kind which in unaltered form contains at least three hydroxyl groups; n is the numeral 1, 2 or 3; and SO₃Z is the typical sulfonic acid radical in which Z represents an ionizable hydrogen atom equivalent.

2. A process for breaking petroleum emulsions of the water-in-oil type, which consists in subjecting the emulsion to the action of a demulsifying agent comprising a compound of the formula type:

in which R.CO.O is a carboxy acid radical derived from a rosin acid; T(OH)_n is a residue derived from a polyhydric alcohol of the kind which in unaltered form contains at least three hydroxyl groups; n is the numeral 1, 2 or 3; and SO₃Z is the typical sulfonic acid radical in which Z represents an ionizable hydrogen atom equivalent.

3. A process for breaking petroleum emulsions of the water-in-oil type, which consists in subjecting the emulsion to the action of a demulsifying agent comprising a compound of the formula type:

in which R.CO.O is a carboxy acid radical derived from a petroleum acid; T(OH)_n is a residue derived from a polyhydric alcohol of the kind which in unaltered form contains at least three hydroxyl groups; n is the numeral 1, 2 or 3; and SO₃Z is the typical sulfonic acid radical in which Z represents an ionizable hydrogen atom equivalent.

4. A process for breaking petroleum emulsions of the water-in-oil type, which consists in subjecting the emulsion to the action of a demulsifying agent comprising a compound of the formula type:

in which R.CO.O is a carboxy acid radical derived from a higher fatty acid; T(OH)_n is a residue derived from a polyhydric alcohol of the kind which in unaltered form contains at least three hydroxyl groups; n is the numeral 1, 2 or 3; and SO₃Z is the typical sulfonic acid radical in which Z represents an ionizable hydrogen atom equivalent.

5. A process for breaking petroleum emulsions of the water-in-oil type, which consists in subjecting the emulsion to the action of a demulsifying agent comprising a compound of the formula type:

in which R.CO.O is a carboxy acid radical derived from a higher fatty acid; T(OH)_n is a residue, free from an ether linkage, and derived from a polyhydric alcohol of the kind which in unaltered form contains at least three hydroxyl groups; n is the numeral 1, 2 or 3; and SO₃Z is the typical sulfonic acid radical in which Z represents an ionizable hydrogen atom equivalent.

sulfonic acid radical in which Z represents an ionizable hydrogen atom equivalent.

6. A process for breaking petroleum emulsions of the water-in-oil type, which consists in subjecting the emulsion to the action of a demulsifying agent comprising a compound of the formula type:

in which R.CO.O is a carboxy acid radical derived from a higher fatty acid; T(OH)_n is the bivalent radical C₃H₅OH; and SO₃Z is the typical sulfonic acid radical in which Z represents an ionizable hydrogen atom equivalent.

7. A process for breaking petroleum emulsions of the water-in-oil type, which consists in subjecting the emulsion to the action of a demulsifying agent comprising a compound of the formula type:

in which R.CO.O is a carboxy acid radical derived from a hydroxylated higher fatty acid; T(OH)_n is the bivalent radical C₃H₅OH; and SO₃Z is the typical sulfonic acid radical in which Z represents an ionizable hydrogen atom equivalent.

8. A process for breaking petroleum emulsions of the water-in-oil type, which consists in subjecting the emulsion to the action of a demulsify-

ing agent comprising a compound of the formula type:

in which R.CO.O is a carboxy acid radical derived from a hydroxylated higher fatty acid; T(OH)_n is the bivalent radical C₃H₅OH; and SO₃Z is the typical sulfonic acid radical in which Z represents a metallic atom.

9. A process for breaking petroleum emulsions of the water-in-oil type, which consists in subjecting the emulsion to the action of a demulsifying agent of the water-soluble type comprising a compound of the formula type:

in which R.CO.O is a carboxy acid radical derived from a hydroxylated higher fatty acid; T(OH)_n is the bivalent radical C₃H₅OH; and SO₃Z is the typical sulfonic acid radical in which Z represents a metallic atom.

10. A process for breaking petroleum emulsions of the water-in-oil type, which consists in subjecting the emulsion to the action of a demulsifying agent comprising a compound of the formula type:

MELVIN DE GROOTE.
